(57) **CLAIM**

I claim the ornamental design for a combination spoon and fork utensil, as shown.

DESCRIPTION

FIG. 1 is a top perspective view of a combination spoon and fork utensil, showing my new design;

FIG. 2 is a slight top perspective view thereof;

FIG. 3 is a slight bottom perspective view thereof;

FIG. 4 is a right side elevational view thereof;

FIG. 5 is a left side elevational view thereof;

FIG. 6 is a slight first end perspective view thereof; and,

FIG. 7 is a slight second end perspective view thereof.
